REFRIGERATING APPARATUS

Martin J. Goulooze, Grand Rapids, Mich., assignor to Nash-Kelvinator Corporation, Detroit, Mich., a corporation of Maryland

Application May 7, 1941, Serial No. 392,209

3 Claims. (Cl. 20—35)

The present invention relates to refrigerating apparatus and more particularly to refrigerator cabinets.

It is an object of the present invention to provide an improved door for a refrigerator cabinet.

It is another object of the present invention to provide an improved door for a refrigerator cabinet having inner and outer panel in spaced apart relation whereby the outer panel is rigidly reinforced for supporting the weight of the door without buckling or twisting, with the inner panel attached in floating relation to permit free expansion and contraction.

The invention itself, however, both as to its organization, and its method of operation together with additional objects and advantages thereof will best be understood from the following description of specific embodiments when read in conjunction with the accompanying drawing, in which:

Fig. 1 is a front view of a refrigerator cabinet embodying the present invention;

Fig. 2 is a rear view of the refrigerator cabinet door with parts broken away;

Fig. 3 is a fragmentary enlarged cross sectional view taken along line 3—3 of Fig. 1;

Fig. 4 is a fragmentary view with parts broken away and parts shown in section taken along line 4—4 of Fig. 3; and

Fig. 5 is a fragmentary enlarged cross sectional view taken along line 5—5 of Fig. 2.

Shown in the drawing is a refrigerator cabinet 10 having a food storage compartment 12 cooled by any suitable refrigerant evaporator of the type now in use (not shown) herein. The cabinet 10 comprises an outer shell 14 and an inner shell or liner 16 in spaced apart relation for placing suitable heat insulation material 17 therebetween and forming insulated top, bottom, rear and side walls enclosing the food storage compartment. The inner liner 16 and outer shell 14 are interconnectively joined together by a breaker strip 19 adjacent the door opening 20 of the compartment 12. The breaker strip together with the inwardly turned portion 22 of the outer shell 14 forms the front wall of the cabinet.

Closing the door opening is a swingably mounted door 25. Gasket 26 extends peripherally about the perimeter of the door and engages the edge 22 of the outer shell to prevent air entering the food storage compartment.

The door 25 is constructed with an outer sheet metal panel 27 formed with upwardly extending sides 29. The marginal edge of the sides are

bent at right angles to form an inwardly extending section 30.

Extending longitudinally about the door and flush against the sides 29 at a parallel distance below the section 30 is a frame member 32. The frame 32 comprises a horizontal section 33 extending inwardly at right angles to side 29, and a leg section 34 lying against and secured by weld, or the like, to the side 29. The end of the leg section is turned at right angles, as at 35.

The horizontal section 33 of the frame extends inwardly a determinable distance beyond the end edges of the section 30. Formed in each of the four corners of section 33 are slots 37 through which pass the ends of the straps 40 which are doubled back and secured by clips 42 to the main portion of the straps. The straps 40 extend diagonally across the door tying opposite diagonal corners of the frame.

Resting on the edge of the frame member 32 is a panel 45 which forms the inner side of the door and is sufficiently spaced from the outer sheet metal panel 27 to provide therebetween for the insertion of heat insulation material 47. The panel 45 is preferably formed of "Bakelite," "Micarta," or other plastic or composition material having a low heat conductivity. It has been found that such compositionally made panel has the tendency to absorb moisture that has condensed on its surface due to the cooled surface with the result that the absorption causes an expansion which if not compensated for causes a buckling or warping of the panel. Further, the expansion is not uniform throughout, but that it may be confined to certain local areas where moisture had condensed and been absorbed, while other areas remain unaffected. Likewise, the expansion may be in accordance to the amount of moisture absorbed in different areas. To permit lateral expansion, the panel 45 is frictionally held by plate 50 against the frame member 32. The plate 50 is secured to the frame member 32 by screws 52 which thread into the upwardly pressed cup shaped section 53. The section 53 serves also as a spacer in preventing the plate 50 from binding the edge of the panel and to allow expansion or contractual movement. The panel 45 is also secured at approximately near its center by screw 55 to the straps 40 at their point of intersection. The shank of the screw 55 is of considerably less diameter than the diameter of the opening 56 in the panel 45 to permit expansional movement of the panel.

The door gasket 26 is formed with a thick-

ened base 60 resting on the frame member. The base 60 narrows as it extends upwardly to provide a constricted neck portion which is vise-like held between the edge of section 30 and the edge of the plate 50 against withdrawal. The plate 50 secures the gasket so as to prevent leakage of air into the interior of the door to thus prevent moisture formation on the inner side of the panel 45. The gasket 26 is formed so as to overlap and conceal the head of the screws 52, and also overlaps and rests upon the section 30.

From the above described arrangement of parts it will be noted that there is provided a door construction whereby the outer panel is reinforced and stiffened independently of said inner panel which is secured thereto in a floating relation.

While I have shown and described the preferred form of my invention, I do not wish to limit myself to the precise details as shown but wish to avail myself of such variation and modifications as may come within the scope of the appended claims.

I claim:

1. A door for a cabinet comprising sheet material to provide side walls with its marginal edge turned to extend inwardly, a reinforcing frame member extending longitudinally in engagement and secured to said side walls, straps joining diagonally opposite corners of said frame mem-

ber, an insulating panel forming the inner side of said door, means for frictionally holding the edges of said panel against said frame member to permit said edges to move relative to said frame member upon the expansion and contraction of said panel, and said means cooperatively securing with said inwardly turned marginal edge a peripherally extending door seal.

2. A door for a cabinet comprising sheet material to provide side walls with its marginal edge flanged inwardly, a reinforcing frame member united to said side wall and extending inwardly at right angles thereto, a strip secured in spaced parallel relation to said frame member forming therewith a laterally opening pocket, and a non-metallic panel member forming the inner side of said door secured by its edges confined within said pocket.

3. A door construction comprising sheet material formed to provide side and front walls with its marginal edge flanged inwardly, a frame carried by said sheet metal at the rear of the door, an insulating panel extending across and forming the rear wall of the door, and means forming a pocket with said frame for frictionally securing said panel to said frame, and a sealing gasket secured between said means and said inwardly flanged edge.

MARTIN J. GOULOZE.
